UNITED STATES PATENT OFFICE.

FREDERICK L. PORTE, OF UTICA, NEW YORK, ASSIGNOR TO UNION SPECIAL MACHINE COMPANY, OF CHICAGO, ILLINOIS, A CORPORATION OF ILLINOIS.

TAPE-HOLDER FOR SEWING-MACHINES.

1,260,039.

Specification of Letters Patent. Patented Mar. 19, 1918.

Application filed April 30, 1912. Serial No. 694,148.

To all whom it may concern:

Be it known that I, FREDERICK L. PORTE, a citizen of the United States, residing at Utica, in the county of Oneida, State of New York, have invented certain new and useful Improvements in Tape-Holders for Sewing-Machines, of which the following is a description, reference being had to the accompanying drawing and to the figures of reference marked thereon.

The invention relates to new and useful improvements in tape holders for sewing machines, and more especially to the means for supporting the tape reel.

15 An object of the invention is to provide a tape holder which may be so adjusted as to vary the tension on the side edges of the tape.

20 In the drawings which show by way of illustration one embodiment of the invention;

Figure 1 is a front view of a sewing machine embodying my invention;

25 Fig. 2 is an enlarged detail showing the tape holder in side elevation;

Fig. 3 is a view similar to Fig. 2, showing a different adjustment of the tape holder;

30 Fig. 4 is an enlarged detail showing the adjustable support for the tape holding bracket, in face view;

Fig. 5 is a similar view showing the adjustable support in edge view.

The present invention consists in a supporting device for the tape holding reel, which supporting device includes a base or standard on which is pivotally mounted a bracket arm carrying the tape reel. This bracket arm is so constructed that it may be adjusted relative to the base or standard, whereby the axis of the tape reel may be inclined relative to the vertical axis of the standard in either direction, so that the distance from the tape guide to the point of delivery of the tape from the tape reel, may be greater at one edge of the tape than at the other, and thereby, a greater tension placed on one edge of the tape than on the other.

50 Referring in detail to the drawings, the improved tape reel is shown in connection with a sewing machine which consists of a work support 1, an overhanging arm 2 in which reciprocates a needle bar 3 carry-

ing needles 4, 4. Coöperating with the needles beneath the work support, are loopers 5, 5. This machine is especially adapted for stitching a binding on to the edge of a body fabric. The body fabric F is passed through the stitching mechanism so that a tape T may be folded by a folder 6 about the edges of the body fabric, and secured thereto by the stitching mechanism. This folder 6 and the stitching mechanism, are of the usual character, and will not need further description. The folder is preferably of the type wherein the strip is folded and inverted as it is led to the stitching mechanism.

The tape T is carried by a tape reel or roll 7. This tape reel is mounted on a stem 8 carried by a disk 9. The disk 9 is provided with a downwardly projecting support 10, which engages and turns freely in a sleeve 11 carried by a bracket arm 12. 75 The bracket arm 12 is pivotally mounted on a standard 13 rising from a base 14 which may be secured to the table on which the sewing machine is mounted. Located in said standard 13 is a rod 15, which is adjustably secured in the standard by set screws 16. The upper end of the rod 15 is formed with a disk-shaped head 17 which is serrated on the side face thereof, as at 18. The bracket 12 is bolted to a depending lug 19 which is also formed with a disk-shaped head 20 having serrations 21 adapted to engage the serrations 18 in the head 17. A bolt 22 passing through the lug secures the same to the head 17 on the rod 90 carried by the standard. By loosening the bolt 22, the two disk-shaped heads may be swung relative to each other, and will be held in various adjusted positions by the inter-engaging serrations. The bracket 12 95 is also provided with a plurality of spaced rods 23 which are alternately staggered relative to each other. The tape passing from the tape reel 7 is led between the rods 23, as clearly shown in Figs. 2 and 3 of the 100 drawings, and these rods serve to place a uniform tension on the tape throughout its entire width.

As the tape passes from the reel to the guiding tension rods 23, it will leave the reel 105 substantially on the line 24. When the bracket arm 12 is adjusted as shown in Fig. 2, it will be apparent that the point 25, where

the tape leaves the reel 7 at one edge thereof, is a greater distance from the tape guide 6, than the point 26 where the other edge of the tape leaves the reel. Therefore, the 5 lower edge of the tape will be placed under slightly greater tension than the upper edge of the tape. On the other hand, when the bracket 12 is adjusted, as shown in Fig. 3, the point 26 will be farther from the tape 10 guide than the point 25, and therefore, the upper edge of the tape will be placed under slightly greater tension than the lower edge of the tape.

From the above description, it will be apparent that by adjusting the bracket 12, the 15 tension on the edges of the tape may be varied to suit the conditions of the tape or the stitching so that the edge of the tape placed on the right side of the goods, may be caused to lie close thereto, without any undesirable 20 looseness, or, if the edge of the tape on the right side of the goods being stitched is found to be too tight for any reason, this may be relieved by a proper adjustment of 25 the bracket supporting the reel.

The term "tape" is herein used in its broadest sense, and is intended to cover a strip of fabric, whether elastic or non-elastic, or whether said strip is formed with selvage edges or with cut edges, and the invention 30 above described is particularly useful for delivering a tape to a guide which is used for folding one edge of the strip to a greater extent than the other, whereby a combined binding and facing strip is produced. By 35 adjusting the bracket holding the tape reel above or below a horizontal plane, the tension on the edge of the binding strip or tape may be varied, so that the combined binding 40 and facing strip will be laid smoothly on the fabric being stitched.

It is obvious that minor changes in the details of construction and arrangement of parts may be made, without departing from 45 the spirit of the invention as set forth in the appended claims.

Having thus particularly described my invention, what I claim as new and desire to secure by Letters Patent, is:—

50 1. The combination of a tape guide, a tape reel for delivering tape to said guide, tension devices between the reel and guide, and means for varying the position of the axis of the reel relative to the guide, whereby a

tension may be placed on one edge or the 55 other of the tape.

2. The combination of a tape guide, a reel for delivering a tape with its side faces substantially vertical to said guide, a bracket arm supporting said reel, and means for adjusting said bracket arm, whereby the inclination of the axis of the tape reel relative to the plane of the tape guide may be varied for placing a tension on one edge or the 60 other of the tape. 65

3. A tape guiding device comprising a standard, a bracket carried by said standard, a tape reel mounted on said bracket, means whereby said bracket may be angularly adjusted relative to said standard, and a plurality of spaced tension rods carried by said bracket. 70

4. A tape guiding device comprising a standard, a rod adjustable in said standard, a bracket, means for adjustably connecting 75 said bracket to said rod, a tape reel carried by said bracket, and a plurality of spaced tension rods mounted on said bracket.

5. A tape guiding device comprising a standard, a rod vertically adjustable in said 80 standard and having a disk-shaped head, a bracket pivoted to said rod and having a disk-shaped head adapted to engage the head on the rod, the contacting faces of said heads being serrated whereby the bracket may be 85 held in adjusted positions, a reel pivotally supported by said bracket, the axis of the reel being at right angles to the longitudinal axis of the bracket. 90

6. A tape guiding device comprising a standard, a rod vertically adjustable in said 90 standard and having a disk-shaped head, a bracket pivoted to said rod, and having a disk-shaped head adapted to engage the head on the rod, the contacting faces of said heads 95 being serrated whereby the bracket may be held in adjusted positions, a reel pivotally supported by said bracket, the axis of the reel being at right angles to the longitudinal axis of the bracket, and a plurality of spaced tension rods carried by said bracket and projecting at right angles therefrom. 100

In testimony whereof, I affix my signature, in the presence of two witnesses.

FREDERICK L. PORTE.
